DENTAL FOIL CONTAINER

Filed Jan. 17, 1930

FIG. I

FIG. 3

FIG. 2

FIG. 4

Inventor.
Lawrence W. Dunham.

By Philip Morris
Attorney.

UNITED STATES PATENT OFFICE

LAWRENCE W. DUNHAM, OF NEW YORK, N. Y., ASSIGNOR TO THE DENTISTS' SUPPLY COMPANY OF NEW YORK, A CORPORATION OF NEW YORK

DENTAL FOIL CONTAINER

Application filed January 17, 1930. Serial No. 421,339.

In dental work in the laboratory, such as in the making of jacket crowns, porcelain inlays and bridge-work, for example, it is customary to use a platinum or alloy matrix foil which, when cut and applied to artificial teeth, facings and inlays, provides a foundation upon which to build up the gold to constitute the real metal supporting structures for the porcelain; and owing to the costly nature of the platinum or other matrix foil, it is desirable that suitable guiding means shall be associated with the foil to enable the same to be cut to the size required without in any wise impairing the smooth character and protection of the foil, whereby the foil remaining is protected against becoming contaminated, wrinkled or marred by handling or by having instruments inadvertently placed upon it.

Broadly considered, my invention comprehends a sheet of platinum or other matrix foil protected within a container or casing in whole or in part of a transparent character, whereby the foil is maintained in a flat condition and, at the same time, shielded or protected against injury, the said container directly provided with, or in association with, markings of a suitable character in the form of lines and perforations, either or both, which will permit the dentist or laboratory worker to approximate and cut from the said foil portions thereof which will be capable of meeting the requirements of the work in hand, with a minimum possible waste or handling of the foil at the time of or after being severed.

More specifically considered, my invention employs marking or indicating means, as a guide in cutting the foil, of such form and character that the foil may be directly marked through the container or cut along lines printed or provided upon the surface of the container, either or both; and preferably the container is made of transparent material whereby the extent and shape of the foil remaining may be readily seen, and by reason of which the cutting of a portion of the requisite size may be assured.

As a further special embodiment in my improved dental foil container, I form the

same of a transparent rectangular body open at one or both ends and closed along its length and within which the platinum or other matrix foil is placed with freedom of adjusting itself longitudinally or transversely of the 55 container by gentle tapping of the same upon its ends or side edges to shift the foil within the casing preliminary to the cutting off of the requisite piece of foil necessary for the work in hand.

As a further distinguishing feature of the preferred form of my improvement, I provide the transparent container in flattened form open at its ends and closed at its side edges and provided, moreover, with perforations at intervals along one of its side edges and additional perforations through the layers constituting its faces, two or more of said perforations positioned in direct alinement with or without line markings indicating such 60 alinement.

My invention further consists of features of construction which are fully described hereinafter and more particularly pointed out in the claims.

Referring to the drawings: Fig. 1 is a side view of my improved dental foil container adapted to receive the matrix foil; Fig. 2 is a plan view of the matrix foil; Fig. 3 is a side view of the container with the foil in 75 place; and Fig. 4 is a cross section of the same, taken on line 4—4.

The container or casing is preferably formed, in whole or in part, of a transparent material, such as celluloid or other substance 80 having similar physical characteristics, and may be made like an elongated envelope without closed ends. As shown, it is formed of a sheet folded along its length at 4 to provide a front wall 2 and a back wall 3. The 85 front wall 2, may furthermore, have a longitudinal flap 5 folded over the edge of the back wall 3 and pressed down upon it, preferably with yielding pressure. The two walls 2 and 3 are pressed close to each other as 90 shown in Fig. 4, and when formed of celluloid or its equivalent, which is pliable under heat and sets upon becoming cold, the walls 95 retain their parallel arrangement, and functionally may be likened to a short length of 100

celluloid tube flattened for its entire length and physically open at its ends. Other features of this container or casing will be specified hereinafter.

In Fig. 2, is shown a thin sheet of platinum alloy or other matrix foil 11, such as employed in the dental arts, more especially useful for making porcelain jacket crowns. This matrix foil 11 is desirably elongated in shape with substantially parallel side edges and of a width somewhat smaller than the width of the container or casing above described. This matrix foil sheet 11 is introduced into the container through the end thereof; and when introduced, it is thoroughly protected but may be shifted within the container by tapping the latter upon the table or fixed surface. For example, the matrix foil is shown in Fig. 3, as adjusted to the longitudinal edge 4 and to one end of the container or casing. To enable the matrix foil 11 to be withdrawn from the container, the latter may have its end notched as at 6 whereby the end of the matrix foil may be grasped and withdrawn to the extent desired.

Assuming that the matrix foil sheet is in position within the container as shown in Fig. 3, there will appear above or in front of the foil a marking, preferably in the form of longitudinal lines, transverse lines and diagonal lines. These may comprise longitudinal line 10a along the edge 4 of the container; a longitudinal line 10 parallel to line 10a and positioned over one of the edges of the foil; transverse parallel lines 14 and 15 parallel to the ends of the container and at right angles to the longitudinal lines 10 and 10a; and oppositely arranged diagonal lines 12 and 13, so that the space within the lines 10, 10a, 14 and 15 may be divided into triangular and diamond shapes; and the latter may, further, be divided into triangles by the addition of a further line 16 parallel to the lines 10 and 10a and centrally located at the junctions of the crossing oblique lines. While I do not restrict myself to the above described markings, they will, however, suffice to provide lines along the container and over the foil whereby the foil and container may be cut, with reasonable accuracy, to the size and form desired.

Aside from the line markings above described, the casing at the junctures of the several lines may be perforated with small apertures, as indicated at 7, 8, 9, and 7a; and in the case of the apertures 9, they may open laterally into the edge 4 of the container. These apertures are very small and their purpose is to provide a means for marking the foil whereby there may be provided upon it, when withdrawn, partly or wholly, from the container, separate punctures or indentations which will act as a guide to the dentist in cutting the foil to the requisite size and shapes, said perforations or indentations en-

abling the cutting of the foil in a manner corresponding to the markings or lines upon the container. In this procedure, the marked foil may be returned to the casing when the desired portion thereof has been severed by means of shears. It will also be understood that in utilizing the foil in the manner just described, the apertures or markings upon the foil itself need not extend beyond that portion of the foil which the dentist knows for a certainty he will not have reason to sever from the main body of the foil.

It will now be seen that the foil is always in full view within the transparent container and, at the same time, it is thoroughly protected against contamination, soiling or injury; and moreover, while it is held in a flat condition, it is capable of being readily shifted within the container to enable it to be positioned beneath the markings upon the container, whereby they act as a guide in cutting, marking or otherwise handling the foil during its commercial use.

By reference to Fig. 4, it will be seen that the closed folded edge 4 provides a wider space between the side walls than occurs along the middle of said container where the side walls 2 and 3 tend to move in direct contact and put a slight pressure upon the foil 11. The enlarged space 4a adjacent to the closed edge 4 is greater than the thickness of the foil, and consequently the edge of the foil does not bind when adjusted down to this closed edge. Moreover, this clearance between the edge of the foil and the closed edge 4 of the container permits the adjustment of the foil by relatively light tapping of the container, while, at the same time, the spring action of the side walls upon the foil places sufficient clamping action between the container and foil to yieldingly retain the latter in any position of adjustment within the container. By reference to Fig. 4, it will also be seen that the upper edge of the side wall 3 is pressed toward the side wall 2 and upon the foil 11 by the spring action of the folded flap 5, and thereby assists in putting a gentle pressure upon the foil to prevent too free shifting thereof.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details as the same are susceptible of modification in various particulars, without departing from the spirit or scope of the invention.

I claim:

1. A combined foil and container consisting of a flattened envelope having an open end and a transparent face having markings

thereon as a guide for cutting the container and its foil contents, wherein said markings are extended to one closed edge of the container and also parallel to and adjacent to the open end of the container.

5 2. The invention according to claim 1, wherein further, the container is provided with apertures in definite spaced positions along the markings of the container to present engaging places on the container for the scissors or other cutting instrument.

10 3. The invention according to claim 1, wherein further, the markings on the transparent face of the container are formed by 15 perforations, and in which a plurality of perforations are positioned in straight alignment and the foil is arranged transversely across the perforations so as to be in alignment with said perforations and thereby in 20 position to be cut.

25 4. A foil container consisting of a flattened envelope having an open end and a transparent face having markings thereon as a guide for cutting the container, wherein further, the container is combined with a flat rectangular foil sheet of less surface area than the 30 interior space of the container, whereby it may be shifted lengthwise and transversely within the container by impact and gravity, and of less thickness than the width of the interior space of the container adjacent to the closed edges of the container.

35 5. A rectangular container formed of a sheet of transparent material folded upon itself to provide flat parallel walls and closed longitudinal edges and open at one end, said closed edges providing more clearance transversely than the distance between the parallel side walls of the container, combined with a 40 flat rectangular foil sheet of less surface area than the interior space of the container, whereby it may be shifted lengthwise and transversely within the container by impact and gravity, and of less thickness than the width of the interior space of the container 45 adjacent to the closed edges of the container.

6. The invention according to claim 1, wherein further, the markings on the transparent face of the container are formed by 50 perforations connected by lines, the said lines being arranged at an angle to each other to form triangular markings, and a portion of the perforations also being arranged along one of the closed edges of the container and forming notches therein at intervals apart to 55 present places on the container for engagement of the scissors or other cutting instrument.

60 In testimony of which invention, I hereunto set my hand.

LAWRENCE W. DUNHAM.
